CLAIM

The ornamental design for a grip for operating lever of working machine, as shown and described.

DESCRIPTION

1. Grip for operating lever of working machine

1.1 : Perspective

1.2 : Perspective

1.3 : Front

1.4 : Back

1.5 : Top

1.6 : Bottom

1.7 : Right

1.8 : Left

1.9 : Reference view showing state of use

The evenly spaced broken lines shown in the drawings are for illustrative purposes only and form no part of the claimed design; the dash-dot broken lines shown in reproductions 1.4 and 1.6 define the boundary of the claimed design and form no part thereof; reproduction 1.9 is a reference view showing the state of the article being placed on a shaft of an operating lever.

1 Claim, 9 Drawing Sheets
